UNITED STATES PATENT OFFICE.

JOHN J. HENNESSEY, OF MILWAUKEE, WISCONSIN.

COMBINED FRICTION AND DIRECT-ACTING DRAFT-RIGGING.

SPECIFICATION forming part of Letters Patent No. 717,679, dated January 6, 1903.

Application filed November 15, 1902. Serial No. 131,460. (No model.)

To all whom it may concern:

Be it known that I, JOHN J. HENNESSEY, a citizen of the United States, residing in Milwaukee, in the county of Milwaukee and State 5 of Wisconsin, have invented a new and useful Improvement in a Combined Friction and Direct-Acting Draft-Rigging, of which the following is a specification.

My invention relates to friction spring draft-rigging for railway-cars.

The object of my invention is to provide a combined friction and direct-acting spring draft-rigging of a simple, compact, strong, efficient, and durable construction capable of 15 being cheaply manufactured and quickly and conveniently applied to the car.

My invention consists in the means I employ to practically accomplish this object or result—that is to say, it consists, in connection with the draw-bar and draft-iron in line therewith having a straight friction-face on one side and double-incline friction-faces on its opposite side, a stationary friction plate or face engaging the straight friction-face of the draft-iron, a transversely-movable friction-block having double-incline friction-faces engaging the double-incline friction-faces on the draft-iron, a transversely-arranged spring acting against said friction-block, a longitudinally-arranged direct-acting spring and followers therefor on the opposite side of the draft-iron from said transversely-movable friction-block, of side plates or stop-castings provided with transverse 25 guides for the transversely-movable friction-block and with longitudinal guides and stops for the followers of the longitudinal or direct-acting spring, the longitudinal guide for said direct-acting spring and followers having an 30 opening closed by said stationary friction-plate for the admission and removal of the direct-acting spring and its followers.

My invention also consists in the novel construction of parts and devices and in the 45 novel combinations of parts and devices herein shown or described.

In the accompanying drawings, forming a part of this specification, Figure 1 is a vertical longitudinal section of a combined friction and direct-acting spring draft-rigging embodying my invention, the section-line being indicated by the line 11 on Fig. 2. Fig. 2

is a plan view, partly in horizontal section, on line 2 2 of Fig. 1. Fig. 3 is a cross-section on line 3 3 of Fig. 1. Fig. 4 is a detail perspective view of the side plates or stop-castings. Fig. 5 is a detail perspective view of the stationary friction-plate. Fig. 6 is a detail perspective view of the thimble. Fig. 7 is a detail perspective view of the stem or rod which 55 extends through the direct-acting spring. Fig. 8 is a detail view of one of the followers.

In said drawings, A represents the draft-timbers; A', the center sills; A², the cross-sills; A³, the buffer-block, and A⁵ the carry- 60 iron.

B is the draw-bar of the coupler B'.

D is the sliding friction draw-bar extension or draft-iron, the same being directly in line with the draw-bar and connected thereto by 70 the clip or yoke b passing through an eye d in the draft-iron, the cross-pivot d' of which eye is slightly rounded or beveled, so that the draw-bar and coupler may have the necessary slight vibratory movement as well 75 as a slight vibratory movement up and down.

F F are the side plates or stop-castings fitting between the draft-timbers and securely attached thereto by bolts f. The draft-iron D has a straight friction-face d² on one side, 80 preferably its upper side, which is in sliding frictional engagement with the stationary but removable friction-plate G, which is securely fixed or anchored on the side plates or stop-castings F F. The draft-iron D has on 85 its opposite side from the said friction-face d², and preferably on its lower side, double-incline friction-faces d³ d⁴, which co-operate with the double-incline friction-faces h h' on the transversely-movable friction-block H, which 90 is acted upon by the transversely-arranged spring K. The friction-block H has a barrel or flange h² to receive the spring K, which is supported at its lower end by a spring-seat or cup K', which is removably secured to the 95 side plates or stop-castings F by cotter bolts or pins K², extending through suitable lugs f³ on the side plates or stop-castings and provided with keys K³. The side plates or stop-castings have transversely-extending guides 100 f⁴ for the friction-block to reciprocate in or on transversely while holding the same in position longitudinally in respect to the draw-bar or draft-iron. The side plates or stop-

castings F F are provided directly above or opposite the friction-block and its transverse guides f^4 with an integral longitudinal guide f^5 to receive the longitudinally-arranged direct-acting spring N and its followers P P. The longitudinal guide f^5 is preferably in the form of a case or housing to cover and inclose the spring N and followers P P, and it has an opening f^6 at its bottom for the admission and removal of the spring N and followers P P, which is closed by the removable stationary friction-plate G, said plate G having a shouldered or raised portion g fitting within said opening f^6 and serving to anchor said friction-plate in place. The stationary friction-plate G thus serves to support and guide the followers P P, as well as to afford a friction-surface for engagement with the straight friction-face d^2 of the draft-iron. The closed ends or heads f^7 f^7 of the longitudinal guide f^5 act as stops for the followers P P. A smaller spring N' may be inclosed within the spring N, if desired. The followers P P are operated by central upright wings d^5 on the draft-iron acting against the removable thimbles P', which are interposed between the followers P and said central upright wings d^5 on the draft-iron. The thimbles P' have sockets p to receive the stem or rod p^2 , which extends through the springs N N'. These thimbles are also preferably provided with flanges p^3 to give a larger bearing against the followers. The thimbles may be made in a separate piece from the followers, as this facilitates the removal and insertion of the followers in the closed guide f^5 .

The two side plates or stop-castings F F are securely bolted together at their meeting faces by bolts f^8 , thus adding strength and rigidity to the draft-rigging as a whole.

The draft-iron D is provided with a central web d^6 , bridging the incline friction-faces d^3 d^4 , to strengthen the draft-iron, said web fitting in a corresponding slot formed in the friction-block H.

To cause the direct-acting spring N to come first into action under either pulling or buffing strains and the transversely-acting spring and friction-block to come subsequently into action, the incline friction-faces d^3 d^4 on the draft-iron are more widely separated than the co-operating friction-faces h h' on the friction-block, thus leaving some play for partial compression of the longitudinal direct-acting spring before the friction-block begins to compress the transverse spring K, and as the downward or transverse movement of the friction-block H is somewhat less than that of the followers P, I prefer to so arrange the parts that the direct-acting spring N is slightly or partially compressed when applied or assembled, as this enables me to use springs of the same size and length and still have both fully compressed by the full movement of the draft-iron, thus utilizing the entire strength of both springs.

I claim—

1. In a combined friction and direct-acting spring draft-rigging, the combination with a draw-bar and draft-iron in line therewith having a straight friction-face on its one side and double-incline friction-faces on its opposite side, a transversely-movable friction-block having double-incline friction-faces engaging the double-incline friction-faces on the draft-iron, a transversely-arranged spring acting against said friction-block, a longitudinally-arranged direct-acting spring and followers therefor on the opposite side of the draft-iron from said friction-block, side plates or stop-castings having transverse guides for said transversely-movable friction-block, and a longitudinal guide for the followers of said longitudinal spring, said longitudinal guide having an open bottom for the insertion and removal of the spring and followers, substantially as specified. 70 75 80 85

2. In a combined friction and direct-acting spring draft-rigging, the combination with a draw-bar and draft-iron in line therewith having a straight friction-face on its one side and double-incline friction-faces on its opposite side, a transversely-movable friction-block having double-incline friction-faces engaging the double-incline friction-faces on the draft-iron, a transversely-arranged spring acting against said friction-block, a longitudinally-arranged direct-acting spring and followers therefor on the opposite side of the draft-iron from said friction-block, side plates or stop-castings having transverse guides for said transversely-movable friction-block, and a longitudinal guide for the followers of said longitudinal spring, said longitudinal guide having an open bottom for the insertion and removal of the spring and followers, and a stationary friction-plate engaging the straight friction-face of the draft-iron and closing the opening in said longitudinal guide, substantially as specified. 90 95 100 105

3. In a combined friction and direct-acting spring draft-rigging, the combination with a draw-bar and draft-iron in line therewith having a straight friction-face on its one side and double-incline friction-faces on its opposite side, a transversely-movable friction-block having double-incline friction-faces engaging the double-incline friction-faces on the draft-iron, a transversely-arranged spring acting against said friction-block, a longitudinally-arranged direct-acting spring and followers therefor on the opposite side of the draft-iron from said friction-block, side plates or stop-castings having transverse guides for said transversely-movable friction-block, and a longitudinal guide for the followers of said longitudinal spring, said longitudinal guide having an open bottom for the insertion and removal of the spring and followers, said longitudinal guide having ends serving as stops 110 115 120 125 130 for said followers, substantially as specified. 130

4. In a combined friction and direct-acting

- spring draft-rigging, the combination with a draw-bar and draft-iron in line therewith having a straight friction-face on its one side and double-incline friction-faces on its opposite side, a transversely-movable friction-block having double-incline friction-faces engaging the double-incline friction-faces on the draft-iron, a transversely-arranged spring acting against said friction-block, a longitudinally-arranged direct-acting spring and followers therefor on the opposite side of the draft-iron from said friction-block, side plates or stop-castings having transverse guides for said transversely-movable friction-block, and a longitudinal guide for the followers of said longitudinal spring, said longitudinal guide having an open bottom for the insertion and removal of the spring and followers, and a stationary friction-plate engaging the straight friction-face of the draft-iron and closing the opening in said longitudinal guide, said longitudinal guide having ends serving as stops for the followers, substantially as specified.
5. In a combined friction and direct-acting spring draft-rigging, the combination with a draw-bar and draft-iron having a straight friction-face on one side and double-incline friction-faces on its opposite side, a transversely-movable friction-block having double-incline friction-faces, a transversely-arranged spring, a longitudinally-arranged direct-acting spring and followers for said longitudinal spring on the opposite side of the draft-iron from said friction-block, a removable stationary friction-block and side plates or stop-castings having integral transverse guides for said transversely-movable friction-block, and a longitudinal guide for the followers of said longitudinal direct-acting spring, said longitudinal guide having an opening closed by said stationary friction-block, substantially as specified.
6. In a combined friction and direct-acting spring draft-rigging, the combination with a draw-bar and draft-iron having a straight friction-face on one side and double-incline friction-faces on its opposite side, a transversely-movable friction-block having double-incline friction-faces, a transversely-arranged spring, a longitudinally-arranged direct-acting spring and followers for said longitudinal spring on the opposite side of the draft-iron from said friction-block, a removable stationary friction-plate, and side plates or stop-castings having integral transverse guides for said transversely-movable friction-block, and a longitudinal guide for the followers of said longitudinal direct-acting spring, said longitudinal guide having an opening closed by said stationary friction-plate, said draft-iron having central upright wings for operating the followers of said longitudinal spring, and said stationary friction-plate having a raised or shouldered portion *g* fitting within the opening of said longitudinal guide, substantially as specified.
7. In a combined friction and direct-acting spring draft-rigging, the combination with a draw-bar and draft-iron having a straight friction-face on one side and double-incline friction-faces on its opposite side, a transversely-movable friction-block having double-incline friction-faces, a transversely-arranged spring, a longitudinally-arranged direct-acting spring and followers for said longitudinal spring on the opposite side of the draft-iron from said friction-block, a removable stationary friction-plate, and side plates or stop-castings having integral transverse guides for said transversely-movable friction-block, and a longitudinal guide for the followers of said longitudinal direct-acting spring, said longitudinal guide having an opening closed by said stationary friction-plate, said draft-iron having central upright wings for operating the followers of said longitudinal spring, and said stationary friction-plate having a raised or shouldered portion *g* fitting within the opening of said longitudinal guide, substantially as specified.
8. In a combined friction and direct-acting draft-rigging, a pair of stop-castings provided with integral transverse guides for a transversely-movable friction-block, and an integral longitudinal guide for the followers of a longitudinally-acting spring, said longitudinal guide having integral ends serving as stops for the followers, substantially as specified.
9. In a combined friction and direct-acting draft-rigging, a pair of stop-castings provided with integral transverse guides for a transversely-movable friction-block, and an integral longitudinal guide for the followers of a longitudinally-acting spring, said longitudinal guide having integral ends serving as stops for the followers, and having also a central opening for the admission and removal of the spring and followers, substantially as specified.
10. In a combined friction and direct-acting spring draft-rigging, a pair of side plates or stop-castings having integral transverse guides for a transversely-movable friction-block and an integral longitudinal guide for the followers of a longitudinally-acting spring, said longitudinal guide being provided with a central opening for the admission and removal of the spring and followers therefrom, substantially as specified.

JOHN J. HENNESSEY.
